[57] CLAIM

The ornamental design for male member of surface fastener, as shown and described.

DESCRIPTION

FIG. 1 is a top plan view of a male member of surface fastener showing our new design;
FIG. 2 is a front view thereof;
FIG. 3 is a rear view thereof;
FIG. 4 is a bottom view thereof;
FIG. 5 is a right side view thereof;
FIG. 6 is a left side view thereof;
FIG. 7 is a fragmentary enlarged view of FIG. 2;
FIG. 8 is a fragmentary enlarged view of FIG. 3;
FIG. 9 is a fragmentary enlarged view of FIG. 5;
FIG. 10 is a fragmentary enlarged view of FIG. 6;
FIG. 11 is a fragmentary perspective view of FIG. 1 from diagonally lower right side thereof; and,
FIG. 12 is a fragmentary perspective view of FIG. 1 from diagonally upper left side thereof.
